PATRICK J. MAGUIRE, OF DETROIT, MICHIGAN.

METHOD AND MEANS FOR DISPENSING CARBONATED BEVERAGES.

1,415,185.

Specification of Letters Patent.

Patented May 9, 1922.

Application filed June 23, 1919. Serial No. 306,204.

To all whom it may concern:

Be it known that I, PATRICK J. MAGUIRE, a citizen of the United States, residing at Detroit, county of Wayne, State of Michigan, have invented a certain new and useful Improvement in Methods and Means for Dispensing Carbonated Beverages, and declare the following to be a full, clear, and exact description of the same, such as will enable others skilled in the art to which it pertains to make and use the same, reference being had to the accompanying drawings, which form a part of this specification.

This invention relates to method and means for dispensing carbonated beverages, and its object is to provide a method and apparatus by means of which beverages having a tendency to foam upon discharge into a receptacle from a supply tank may be discharged practically without foaming. Heretofore in the dispensing of the carbonated beverages such for instance as ginger ale, the pressure under which the liquid in the supply tank is maintained causes an excessive foaming upon release of pressure and simultaneously with the discharge of the beverage and this results in excessive amount of time consumed in drawing the beverage. The principal feature of this invention is involved in the method and means of first drawing the carbonated liquid from the supply tank into a sealed receptacle provided with an air chamber at the upper end into which atmosphere of the receptacle is forced by the inflowing fluid so that when the receptacle is filled the liquid therein is still under practically an equal pressure to that in the supply tank and, upon the opening of the valve for discharge of the liquid, the pressure on the surface of liquid is released only partially due to the fact that the pressure will be maintained to a certain extent by leakage from the said air chamber whereby the pressure is not entirely relieved instantaneously but on the contrary is released gradually so that foaming is not produced. This general object and the several novel features of the construction of an apparatus by means of which the object may be attained are hereinafter more fully described and claimed and the preferred form of apparatus is shown in the accompanying drawings in which—

Fig. 1 is a vertical section of a dispensing apparatus embodying my invention.

Fig. 2 is a perspective view of a valve utilized in the discharge line.

Fig. 3 shows an alternative form of construction of a receptacle into which the beverage is first drawn from the supply tank previous to its being dispensed.

The supply tank and intermediate pressure releasing tank may be positioned in any convenient manner preferably hidden from view for instance by being placed back of a shield or wall member 1 so that only the discharge faucet, indicated at 2, is exposed to public view. Such disposition of the apparatus, however, is not essential as the several elements may be disposed in any manner found convenient.

The beverage to be dispensed is the usual supply tank 3 under pressure and this tank is provided with the usual discharge valve 4 connected with a conduit 5 leading to the coils 6 of a refrigerating unit by means of which the beverage is cooled prior to dispensing. In the preferred form of construction, the pipe 7 leads

from the cooling coils into a tubular member 8 extending through the partition 1. 80

This tubular member is provided at the forward end with a valve 9 secured to the end of the casing 8. This valve member is provided with the usual tapered valve 10 main-

tained on its seat in the usual manner as by 85 a nut 11 on the threaded projecting stem at the small end of the valve. On the inner end of this casing 8 is supported a hermetically sealed receptacle 12, and a second con-

duit 13 leads from the valve seat to the interior of the receptacle 12 at the bottom as 90 shown. A third conduit 14 leads from the valve seat into the receptacle 12 terminating close to the horizontal partition 15 formed

in the receptacle dividing the same into a 95 lower chamber 16 and an upper chamber 17. The several pipes 7, 13 and 14 may be ar-

ranged in any convenient manner either by the formation of the channels in a single member or by means of pipes here shown 100 carried in the casing enclosing the same and the connection of the conduits or pipes with the receptacle 12 and the valve member are leak proof.

As will be understood from the above 105 description the valve seat has three openings on one side thereof with which the conduits 7, 13 and 14 communicate respectively, the tubes preferably being arranged in vertical alignment as shown. Diametri-

cally opposite the tube openings in the valve seat is a discharge opening 18 and also a vent opening 19. The discharge end of the valve may be of any approved character being here shown as having a depending tubular discharge conduit 20 connected therewith preferably of a length practically equal to the depth of the glass into which the beverage is to be dispensed so that the 5 glass may be held with the bottom close to the discharge end of the conduit 20. The valve body 10 is provided with a groove 21 extending nearly entirely around the valve, the ends thereof being spaced as 10 indicated at 21^a in Fig. 2. This groove 21 registers with the end of the conduit 14 as will be understood from Fig. 1 and, when in registration therewith, the upper 15 end of the chamber 16 is vented to atmosphere through the vent 19. By turning the valve so that the space 21^a registers with the end of the conduit 14 the said conduit is closed and the receptacle sealed.

Directly beneath the said portion 21^a of 20 the valve is a vertically elongated recess 22 formed in the valve body of a length and size to register with the ends of both conduits 7 and 13 simultaneously, the size of the recesses being slightly greater than the 25 diameter of both the conduits so that when in registration therewith, there is an unrestricted flow through the conduits into the chamber 16. It is to be noted that, when the recess 22 is turned to registration with the conduits 7 and 13, the portion 21^a of the valve seals the end of the conduit 14. Therefore, upon so turning the valve to bring the recess 22 into registration with the conduits as stated, fluid may flow from the 30 supply tank under pressure into the chamber 16. With the chamber 16 empty, the flow of fluid thereinto from the supply tank compresses the air or gas in the receptacle forcing it to the upper end thereof through 35 the valve 23 in the dividing wall 15 into the chamber 17. This wall also has a small aperture 24 therein through which gas may flow, it being restricted in flow due to the smallness of the aperture which is only 40 about one-thirty-second of an inch in diameter. The size of the chamber 16 is such that prior to the time the said chamber becomes 45 filled with liquid the pressure of the air therein will equal the pressure of the supply 50 tank and, therefore, the level of the liquid will be about as indicated by the dotted lines 25 below the upper open end of the conduit 14. With the chamber 16 filled substantially as indicated and under 55 pressure on the surface of the liquid and in the chamber 17, which is substantially equal to that of the supply tank, foaming of the liquid is prevented during the filling of the receptacle.

60 The valve member 10 also has an aperture

65 extending diametrically therethrough adapted to register with the end of the conduit 13 and the aperture 18 in the end of the valve case 9 which is the position of the parts in Fig. 1. When the valve is 70 thus turned the groove 21 is in registration with the discharge end of the tube 14 which vents the tube to atmosphere releasing the pressure at the surface of the liquid in the chamber 16. Due to the action of the gas 75 under pressure in the chamber 17, the valve 23 (which may be of any approved type) is closed upon release of pressure in the chamber 16 but, by reason of the small opening 24, gas or air under pressure may 80 flow in a restricted manner into the chamber 16. This does not allow an instantaneous release of the pressure on the fluid and there is therefore no great tendency for the fluid to foam in the chamber 16 upon the opening of the valve 10. The fluid during discharge is under a gradually decreasing pressure and by gravity flows through the conduit 13 into the discharge end of the faucet and as the liquid is drawn the pressure thereon is partially maintained from the chamber 17 thus checking the tendency 85 to foam.

90 As before stated, several types of valves are suitable for use in the partition 15, an alternative form of which is shown in Fig. 3. This simply consists of a rubber tube 30 open to the chamber 16 and extending into the chamber 17 and is therein provided with a slit 31 in one side thereof which opens 100 upon the pressure from the interior produced by a flow of liquid into the chamber 16 and is closed by pressure on the exterior in the chamber 17. The dividing wall 15^a in this case is likewise provided with the small leak¹⁰⁵ aperture 32 corresponding to that shown in Fig. 1. In any case the valve member in the partition wall is such as to allow a free flow of air or gas into the chamber 17 and prevent flow of air therethrough from the 110 chamber 17 or be closed by pressure in the chamber 17 when in excess of that in the chamber 16.

115 From the foregoing description it becomes evident that, by the arrangement of an intermediate double chambered receptacle into which the fluid from the supply tank is first discharged under pressure and the provision 120 of a leakage from the upper into the lower chamber upon discharge of the liquid, that the pressure on the liquid is partially but not entirely released upon venting the chamber 16, and that as the liquid is drawn a gradually decreasing pressure is maintained preventing an effervesing and thus the liquid 125 may be drawn into a glass practically clear or "flat." Upon the opening of the valve to permit a discharge from the intermediate chamber, the pressure is reduced and the liquid flows from the chamber without excess- 130

sive force due to the pressure and, although some slight foaming may take place at the surface of the liquid, the discharging of the liquid from the bottom of the receptacle 5 avoids the drawing of the foam.

Having thus fully described my invention, what I claim is—

1. The method of dispensing carbonated beverages which consists in first discharging 10 the beverage from a supply tank into a sealed receptacle under pressure equal to that of the supply tank, the sealed receptacle having an upper and a lower chamber and a passageway permitting a restricted flow of 15 gas from the upper to the lower chamber, suddenly relieving the pressure on the lower chamber, and then discharging the liquid while under reduced pressure caused by the 20 restricted flow of the gas from the upper chamber.

2. In apparatus for dispensing carbonated beverages, a supply tank in which liquid is stored under pressure, a receptacle normally sealed to atmosphere and having an upper 25 and lower chamber and a passageway therebetween permitting a comparatively free flow of gas from the lower to the upper chamber and a passageway permitting a restricted flow in the opposite direction, means 30 for discharging the fluid from the bottom of the lower chamber and momentarily releasing the pressure on the surface of the liquid therein.

3. In apparatus for dispensing liquid 35 under pressure, a supply tank in which the liquid is maintained under pressure, a receptacle normally closed to atmosphere, the

receptacle having an upper and lower chamber and a passageway permitting a restricted flow of gas therebetween, a passageway 40 permitting free flow of gas only from the lower to the upper chamber, the flow of liquid from the tank into the receptacle pocketing a gas in the upper chamber, means for discharging the fluid from the bottom chamber and simultaneously releasing the pressure on the surface of the liquid in the said chamber, the flow through the restricted aperture maintaining a partial pressure on the surface of the liquid during its withdrawal. 45

4. In dispensing apparatus for dispensing liquids under pressure, the combination with a supply tank for maintaining the liquid under pressure, of a receptacle normally closed to atmosphere having an upper and a lower chamber, there being a passageway permitting a restricted flow of gas from one chamber into the other and the flow of liquid into the receptacle, pocketing a gas in the upper chamber under pressure substantially equal to that in the supply tank, a valve in the wall between the chambers opening by pressure in the lower chamber and closing by pressure in the upper chamber when in excess of that in the lower chamber, 65 a valve for discharging the liquid from the bottom of the lower chamber, means controlled by the valve opening the upper end of the lower chamber to atmosphere upon opening of the valve to discharge the liquid. 70

In testimony whereof, I sign this specification.

PATRICK J. MAGUIRE.
